BOTTLE-CAPPING MACHINE.

1,135,680.

Specification of Letters Patent.

Patented Apr. 13, 1915.

Application filed October 27, 1913. Serial No. 787,554.

To all whom it may concern:

Be it known that we, JOHN J. GAYNOR and PETER CARL LIEBER, citizens of the United States, and residents of Indianapolis, county of Marion, and State of Indiana, have invented a certain new and useful Bottle-Capping Machine; and we do hereby declare that the following is a full, clear, and exact description thereof, reference being had to the accompanying drawings, in which like letters refer to like parts.

The object of this invention is to improve the construction of compensating mechanism in bottle capping machines of the type set forth in the application of John Gaynor and Peter Carl Lieber, Serial No. 786,030, filed August 21, 1913, for bottle capping machines.

One feature of the invention consists in the improvement of the compensating device for supporting bottles and particularly in the employment of a dog pivotally mounted at its upper end and with its lower and free end adapted to be supported by inclined surfaces of which it may slip when the strain becomes sufficiently great and thereafter wedged between two surfaces, said wedging action resisting the downward movement of the bottle support and yet being sensitive to the needs of movement of the bottle support to accommodate various bottles. To that end upon one side of said dog at its lower end there is a shoulder of slight inclination adapted to rest upon a corresponding inclined surface of a stationary plate and be held thereon by a spring supported plate having at its upper end a considerably inclined surface and preferably a convex surface bearing against a similarly inclined and convex surface of the dog. When the strain becomes too great, the dog is pushed off the fixed plate and the movable plate correspondingly yields. One great advantage in the construction which is set forth herein is that the dog is self sharpening and automatically retains its peculiar form and also its action is controlled by a light spring, but the pressure is dependent upon the friction created by the dog having the surface referred to. Said dog is con-

tained within a post and operates within a recess in such post and said post is connected with the bottle support. The bottle support is telescoped having an upper tube adapted to telescope over a lower tube comparatively stationary. Along with the foregoing is a lubricating arrangement whereby the lubricating oil is caused to circulate by reason of the movement of the parts of the compensating device.

Another feature of the invention consists in the stop construction for limiting the return or downward movement of the bottle support.

Still another feature of the invention consists in means for preventing the chipping off of the lip of the bottle by the throat of the crowning plate, particularly after the plunger mechanism has worn so as to permit the mouth of the bottle to enter the throat too far. This is done by providing a hole in the upper end of the plunger and inserting an extension with a pin in it so that it is readily removable and extensions of various thickness can be employed, as the occasion requires and they are located so as to be inaccessible unless the machine is dismembered and, therefore, nobody can intentionally or accidentally affect the machine so as to cause it to chip the upper ends of the bottle.

The nature of the invention will be understood from the accompanying drawings and the following description and claims.

In the drawings, Figure 1 is an elevation of a bottle capping machine with parts broken away and with the casing in central vertical section. Fig. 2 is an elevation of a bottle and a central vertical section through the crowning head, both on an enlarged scale. Fig. 3 is a section on the line 3-3 of Fig. 1, on an enlarged scale and with parts broken away at the bottom and showing the parts in their normal and locked position. Fig. 4 is the same showing the parts in actuated or unlocked position. Fig. 5 is a section on the line 5-5 of Fig. 3. Fig. 6 is a perspective view of one of the removable extensions on the upper end of the plunger in the head. Fig. 7 is a perspective view of 10

a washer adapted to be used, if desired, with said movable extension.

The drawings herein illustrate a type of bottle capping machine which is in practical use and has a base 10 and casing 11 with a driving shaft 12 and driving pinion 13 meshing with a driving gear 14 for turning the tubular bottle supports 15 and causing the rotation of an annular series of such bottle supports. Said bottle supports reciprocate their upper ends through a table 16 and centrally through said table a column 17 extends which carries the crowning head plate 18.

20 is a bottle in position to be crowned.

The foregoing mechanism is old and constitutes no novel part of this invention excepting in connection with improvements hereafter set forth.

20 The bottle support 15 upon which the bottle rests has at its lower end a tube 21 which surrounds and telescopes on the upper end of a compensating tube 23 and within the round tube 23 a rectangular tube 24 is

25 secured by a set screw 25. The bottle supporting tube 21 has a bar 26 extending downward from it through the tubes 15 and 24 and lying against the inner wall of the tube 24 and having a longitudinal recess 27 there-

30 in. In the upper pocket of said recess the upper end of a dog 28 lies. The lower end of said dog is free with a long beveled surface 30 on one side and a notched recess on the other side with a short beveled shoulder

35 31. The extreme lower point is convex, substantially as shown in Fig. 3, so as to wedge in between two plates 32 and 33. The plate 32 is fixed and is secured to the inner surface of the square tube 24 and it has a bevelled shoulder 33 corresponding with the shoulder 31 on the dog 28, both of said shoulders being inclined about thirty degrees from a horizontal line. The plate 35

40 is movable, being supported by a spring 35 mounted on an adjusting nut 36 on a bolt 37 in a plate 38 secured to the lower end of the bar 26 by a screw 39. The upper end of the movable plate 33 is beveled at 40 to correspond with the bevel 30 on the lower end

45 of the dog 28, said two surfaces being bevelled so as to be about thirty degrees from a vertical line, but somewhat convex, as shown.

In operation the parts are normally in the 55 position shown in Fig. 3, the lower end of the dog resting by means of its shoulder 31 on the shoulder 34 of the plate 32 and wedging against the bevel 40 of the movable plate 33. If the downward strain during the capping of a bottle upon the bar becomes excessive, the downward pressure of the dog 28 will cause it to be pushed toward the movable plate 33 by the shoulder 34 on the plate 32 which is fixed to the square stationary

tube 24 and a further downward movement 65 of the dog 28 will cause the inclined surface 30 of said dog to bear against the inclined surface 40 and force the movable plate 33 downward against the action of the spring 35, as indicated in Fig. 3. By reason of the 70 slight degree of bevel of the shoulders 31 and 34 it will require a certain amount of strain before the dog 28 will be pushed off against the plate 33 sufficiently to force it downward. Therefore, when bottles vary- 75 in size are being capped, this yielding or compensating means for supporting the bottles will allow for such variations in the sizes of the bottles and even after the dog 28 has been dislodged from the shoulder 34 on the 80 fixed plate 32, the beveled surfaces 30 and 40 will still cause sufficient friction between the dog and fixed plate 32 to prevent any sudden downward movement of the bottle support and, therefore, the contents of the bottle will 85 not be agitated by the machine during the capping.

The downward movement of the tube 15 is limited by a pin 45 which extends diametrically through said tube and the bar 26 engag- 90 ing a collar 46 secured to and surrounding a tube 47 which surrounds and is secured to the intermediate portion of the column 17. The bottle supporting mechanism is elevated by a cam track 52 secured to the column 17 95 and projecting laterally outward and upon it rollers 51 ride, said rollers being secured to the lower ends of the tube 23. At the lower end of said tubes 23 there is also an inwardly extending arm 53 projecting be- 100 neath the cam track 52 so that said cam track acting upon said arm will forcibly return the bottle supporting mechanism, if one does not wish to rely merely upon gravity for causing such return.

105 Another feature of the invention consists in the means for preventing the shearing off of the lip of the neck of a bottle when for any reason the bottle is raised by the machine too high in the throat of the capping device. This is a very serious difficulty as it destroys a great many bottles during the operation of machines of this type. In the crowning head mechanism, the plate 18 is provided with a conical recess 60 in which 110 the mouth of the bottle projects and wherein the crown or cap 61 is forced upon the lip of the bottle by the lower end of a plunger 62 resisting the elevating movement of the bottle support. The plunger is mounted in 115 a case 63 extending upward from the plate 18. Said plunger has a shoulder 64 at its lower end against which a spiral spring 65 acts downward, said spring surrounding the plunger and lying between the shoulder 64 120 and screw cap 66. The case 63 and screw cap are arranged so that the plunger will have only a slight movement and the upper

end of the plunger is provided with a central recess 67 in which the reduced end 68 of an extension 69 extends. This extension limits the upward movement of the plunger to 5 suit the bottle. Preferably in the beginning the throat 60 and the case 63 and cap 66 are arranged so that no extension is needed and the mouth of the bottle will not be permitted to enter the throat so far as to have the lip 10 thereof chipped or injured. As the throat and plunger wear, such wear must be taken up and this is accomplished by adding the extension 69, using an extension of suitable thickness. As the wear becomes greater, a 15 washer 70 may be added.

For the purpose of lubricating the compensating construction an oil duct 80 leads from a chamber below the movable plate 33 through the body of the post 26 to the chamber 20 above said movable plate. Also there is a duct 81 leading from said upper chamber through the tube 24. The chambers within the tubes 23 and 24 are charged with oil and as the parts vertically reciprocate, the oil 25 is pumped or forced upward through said oil ducts to the upper chamber so as to circulate the lubricating oil.

From the foregoing it is seen that the compensating mechanism is simplified and 30 the parts are durable and efficient. The dog 28 is self-sharpening. By that is meant that the pressure of the movable plate 33 against the lower end of the dog causes the shoulder 31 on the dog to wear straight in its frictional engagement with the shoulder 34 on the plate 32, and the vertical surface of the extreme lower end of the dog will bear also 35 against the plate 33 and keep it worn so that the shoulder 31 and said vertical surface will remain of the same dimensions and at the 40 same angle with each other as the dog wears. The same thing is true of the opposite surfaces on the plate 32, so that after long use these various engaging surfaces between 45 the dog and plate 32 will be the same as in the beginning. The engaging surface between the dog and plate 33 will also wear and tend to sharpen the dog, but the wear will be compensated for by the spring before 50 mentioned and the further sharpening of the point of the dog on the side next to the plate 33 will tend to promote the wedging action of the plate 33 against the dog.

It is also to be noted that with the oil 55 lubrication, the frictional surfaces between the dog and two plates will always be thoroughly and automatically lubricated. Also a positive means is provided for limiting the return movement of the bottle holder 60 regardless of any wear or variation in the cam track 52 below.

It is also clear that the machine can be adjusted to prevent the chipping of the mouths of the bottles and avoid great loss

in the operation of such machines, and the 65 adjustable means is inaccessible during the operation of the machine so that no one can accidentally or intentionally change the operation of the machine. This is a very important feature of the invention. 70

The invention is:

1. A bottle capping machine including a bottle support, a dog for supporting said bottle support, and yielding means for resisting the downward movement of the lower 75 end of said dog and having an inclined surface engaging said dog so that the dog will be self-sharpening.

2. A bottle capping machine including a bottle support having a vertical recess there- 80 in with a pocket in its upper end, a dog for supporting the bottle support with its upper end located in said pocket, and yielding means for resisting the downward movement of the lower end of the dog.

3. A bottle capping machine including a bottle support, a relatively stationary tube within which the lower portion of said bot- 85 tle support is reciprocated, a dog for sup- porting said bottle support, means on said stationary tube for frictionally resisting the downward movement of the lower end of the dog, and yielding means for resisting such movement of the dog.

4. A bottle capping machine including a 95 bottle support, a relatively stationary tube within which the lower portion of said bot- tle support is reciprocated, a dog for sup- porting said bottle support, means on said stationary tube for frictionally resisting the 100 downward movement of the lower end of the dog, and yielding means tending to hold the dog in frictional engagement with said fixed means and resisting the downward move- 105 ment of the dog after it has escaped from said fixed means.

5. A bottle capping machine including a bottle support, a tube in which the lower part of the bottle support telescopes, a plate secured to the inner wall of said tube with 110 the upper edge thereof beveled downwardly, a dog for supporting said bottle support having an inclined shoulder adapted to rest upon the inclined upper surface of said plate, and yielding means for holding the 115 lower end of said dog on the upper end of said fixed plate until the strain forces the dog off of said plate and thereafter resisting the downward movement of the dog.

6. A bottle capping machine including a 120 bottle support, a tube in which the lower part of the bottle support telescopes, a plate secured to the inner wall of said tube with the upper edge thereof beveled downwardly, a dog for supporting said bottle support 125 having an inclined shoulder adapted to rest upon the inclined upper surface of said plate, a downwardly movable plate bearing

against the wall of the recess in said bottle support on one side and with an inclined surface bearing on the lower end of said dog so as to force said dog toward said fixed plate, and a spring tending to force said movable plate upward.

In witness whereof, we have hereunto af-

fixed our signatures in the presence of the witnesses herein named.

JOHN J. GAYNOR.

PETER CARL LIEBER.
